SECRET SIGNALING SYSTEM

Ellsworth D. Cook, Scotia, N. Y., assignor to General Electric Company, a corporation of New York

Application July 31, 1940, Serial No. 348,758

12 Claims. (Cl. 250—6)

My invention relates to radio signaling systems, particularly to secret signaling systems, and its general object is to provide signaling systems in which any desired high degree of secrecy is obtained by means including frequency modulations of a carrier wave.

In accordance with the present invention this object is attained by the provision of a secret signaling system in which two frequency modulations of the carrier wave are employed in succession, one modulation being in accordance with a desired signal and one in accordance with a distorting signal.

The novel features which are considered to be characteristic of my invention are set forth with particularity in the appended claims. The invention itself, however, both as to its organization and method of operation together with further objects and advantages thereof may best be understood by reference to the following description taken in connection with the accompanying drawings in which Fig. 1 is a diagrammatic representation of a secret signaling system embodying my invention, Fig. 1a illustrates diagrammatically a construction detail of the system shown in Fig. 1, and Fig. 2 represents a secret signaling system based upon the system of Fig. 1.

Referring to Fig. 1, the numerals 1 and 2 designate respectively a transmitter and a receiver for a secrecy signaling system. In the transmitter 1 a source of oscillations indicated by the numeral 3 is provided for generating a carrier wave of suitable frequency. Numeral 4 designates an antenna from which the carrier is transmitted after modulation by desired signals which are distorted in a manner to be explained hereinafter.

In series between oscillator 3 and antenna 4 are connected a frequency modulator 5 preferably including means (not shown) to adjust the frequency shift thereof, a linear amplifier 6, a second frequency modulator 7 also including means to adjust the frequency shift thereof, a second linear amplifier 8, an amplitude modulator 9, and a power amplifier means 10 which represents one or more amplifiers for raising the level of the signal to be supplied to the antenna.

To impress a distorting signal upon the first frequency modulator 5, a source, 11, of oscillations adjustable over a suitable range is provided which is connected to an amplifying and harmonic generating device 12, connected in turn through an amplifier 13 to the modulator 5. To impress upon frequency modulator 7 the desired signals to be transmitted, the latter modulator is connected through an amplifier 14 to a source (not shown) of these desired signals.

To provide a synchronizing signal for the transmitter 1 and the receiver 2, oscillator 11 is connected to the amplitude modulator 9.

To prevent interception of the distorting signals from the transmitter when the desired signals are not being radiated, an interlock 15, described more fully hereinafter, is connected between the amplifier 14 of the desired signals and the amplifier 13 of the distorting signals.

10 The frequency modulators 5 and 7 may be of any suitable construction in accordance with well-known principles.

The amplifying and harmonic generating device 12 may be constructed in various ways. For example, device 12 may include doublers, triplers, and mixing stages, (all not shown), of such form and so arranged that any desired harmonic of the frequency supplied by the oscillator 11 may be obtained. In harmonic generating device 12, the 15 fundamental and the second to the seventh harmonics thereof are obtained respectively through corresponding control means 16 to 22 each comprising a means, as indicated by the arrows, for adjustment of magnitude of the harmonic, and 20 a switch means, such as the pairs of sockets 23 to 29 adapted to cooperate with plugs 30 to 32, to connect in series various of the harmonic generating means of device 12 to the amplifier 13. The device 12, with the associated control means 16 to 22, may thus be employed to obtain desired 25 wave shapes by adding together various components of the wave supplied by oscillator 11, having different magnitudes.

In the receiver 2 of Fig. 1 the initial stages 30 thereof which include an antenna 33, a radio frequency amplifier 34, an oscillator 35, a converter 36, and an intermediate frequency amplifier 37, may be of a usual superheterodyne receiver type. The output of the intermediate frequency amplifier 37 is connected to two channels 38 and 39.

40 In the channel 38 the output of intermediate frequency amplifier 37 is impressed upon a rectifier 40 which is connected through a filter 41 to an amplifying and harmonic generating device 42. The device 42 is similar in all respects 45 to the device 12 of the transmitter 1, having similar amplitude control means, as 43, 44 and 45, and similar switch means, as plugs and sockets 46 and 47, 48 and 49, and 50 and 51. As in the device 12, in device 42 any combination of the fundamental and the second to the seventh harmonic 50 may be selected by the switch means.

In the other channel, 39, of receiver 2, the output of intermediate frequency amplifier 37 is impressed upon a converter 52. The output of the 55 amplifying and harmonic generating device 42 is

impressed upon a frequency modulator 53 to which is connected an oscillator 54, and the output of frequency modulator 53 is also impressed upon the above-mentioned converter 52. The converter 52 is connected through a limiter 55 to a frequency modulation-to-amplitude modulation converter 56, and the latter converter 56 is connected through an amplifier 57 to a signal reproducing device or loud speaker 58. An amplifier (not shown) may be added between the converter 52 and the limiter 55.

In operation of the secrecy signaling system illustrated in Fig. 1, a carrier wave, the frequency of which, for purposes of illustration, may be in the 40 to 80 megacycle range, is supplied to frequency modulator 5 of transmitter 1 from oscillator 3. A wave, the frequency of which may be in the 500 to 5000 cycle range, is supplied to amplifier and harmonic generator 12 from oscillator 11. A distorting signal is supplied to frequency modulator 5 through amplifier 13 from device 12. The distorting signal in the illustrated case is constituted by a combination of the fundamental supplied by oscillator 11 and selected from device 12 by plug 30 and socket 23 of control means 16, the third harmonic of this fundamental selected by plug and socket 31 and 25 of control means 18, and the fifth harmonic of the fundamental, selected by plug and socket 32 and 27 of control means 20.

The carrier wave from oscillator 3, frequency modulated in modulator 5 and having impressed thereon the distorting signal from device 12, is then impressed upon the second frequency modulator 7 through amplifier 6. A desired signal from the signal source (not shown) is impressed upon the second frequency modulator 7 through the amplifier 14.

The frequency modulator 7 to which the desired signal is applied from amplifier 14 thus receives, from the amplifier 6, a carrier wave which has already been frequency modulated, in modulator 5, according to a complex wave form or code signal supplied through the amplifier 13 and derived from the amplifier and harmonic generator 12. The total distorting signal impressed upon frequency modulator 7 is composed of three independent components, i. e., the average frequency supplied by oscillator 11, the frequency shift superimposed upon the radio frequency carrier wave by the frequency modulator 5, and the wave shape of the distorting signal supplied by the harmonic generator 12.

Therefore the frequency modulated desired signal which leaves frequency modulator 7 is distorted, and unintelligible if received by an ordinary frequency modulation or amplitude modulation receiver. In selecting the total distorting signal a large number of combinations of the three independent components may be employed, and in operation of the transmitting station 1 and the corresponding receiving station 2 the combination to be used will be determined in accordance with a previously arranged code agreed upon by the operators respectively of the transmitting and receiving stations.

The distorted signal from modulator 7 is supplied through amplifier 8 to amplitude modulator 9. Oscillations of the frequency of oscillator 11, or harmonics thereof which may be obtained from the harmonic generator 12, are also impressed upon the amplitude modulator 9. The amplitude modulation thus introduced into the signal is preferably small, for example of the order of 20%, and its purpose is that of a synchronizing signal

for decoding of messages at the receiver. The operation of this synchronizing signal will be explained more fully hereinafter. The complete signal from amplitude modulator 9 is impressed through power amplifier 16 upon the antenna 4 and radiated therefrom.

During periods when no speech or other desired signals are being sent from the signal source through amplifier 14, only the distorting signal comprising the carrier which is frequency-modulated by the complex wave form would be radiated from antenna 4 in the absence of preventive means. Therefore, the distorting signal could be easily intercepted and analyzed at a receiving station not provided with the above-mentioned code, and a similar distorting signal could be introduced at the latter station thereby to intercept the transmitter signal when it contained the speech signal. Referring more particularly to Fig. 1a, to prevent such undesired intercepting of the distorting signal the interlock 15 is interposed between amplifiers 14 and 13. This interlock may comprise a rectifier 15a supplied with current from amplifier 14 and arranged to provide a voltage, across a resistor 15b for example, which voltage normally overcomes a high bias voltage, impressed from a suitable source 15c upon the grid of amplifier 13 and permits the latter to transmit the wave from device 12. The amplifier 13 is, however, blocked when the speech signal stops, thereby preventing the radiating of the distorting signal from the transmitter in the absence of the speech signal.

The radiated carrier wave, of 40 megacycle frequency for example, modulated as hereinabove described by a desired signal and a distorting signal, is impressed upon the antenna 33 of receiver 2 from the antenna 4 of transmitter 1. The superheterodyne initial stages of the receiver 2 may be so arranged that the intermediate frequency from these stages is, for example, 20 megacycles.

The portion of the 20 megacycle modulated carrier wave impressed from intermediate frequency amplifier 37 upon rectifier 40 in the branch 38 contains the component, utilized as a synchronizing signal, which has been impressed upon the transmitted signal by the amplitude modulator 9 of transmitter 1. This component, appearing in the output of rectifier 40, is, in the present case, of the same frequency as that of the output of oscillator 11 of Fig. 1. The output of the rectifier 40 is passed through the filter 41 which is so arranged that undesired frequencies are removed leaving the above-mentioned component. The output from the filter is then impressed upon the amplifying and harmonic generating device 42. The fundamental frequency and the third and fifth harmonics of the fundamental, which are respectively of the same frequency as the corresponding fundamental and third and fifth harmonics from device 12 of Fig. 1, are selected from the device 42 by plugs and sockets 46 and 47, 48 and 49, and 50 and 51, and the control means 43, 44 and 45 are so adjusted that the several components are respectively of the same amplitude as the corresponding components from the device 12 of transmitter 1.

The coding signal wave, or wave of complex form derived from the device 42 by the combining of the fundamental and its third and fifth harmonics is therefore identical with the coding signal wave, or wave of complex form, derived from the device 12 of the transmitter 1. The fundamental frequency, which is the same in

harmonic generator 12 of the transmitter 1 and in harmonic generator 42 of the receiver 2, thus serves to synchronize the frequencies of the coding signal or complex wave at the transmitter 1 and the receiver 2.

The received modulated carrier wave is impressed from intermediate frequency amplifier 37 upon converter 52 also, in the other branch 39 of the receiver 2. The converter 52 performs two functions. In this converter the frequency of the wave impressed thereon is reduced from the intermediate frequency, in the present case 20 megacycles, to a still lower frequency, for example six megacycles. Further, in the converter 52 the distorting frequency modulation introduced into the radiated signal by the frequency modulator 5 of the transmitter 1 is removed. For these purposes the wave of complex form from device 42 is utilized to frequency-modulate the wave having a frequency of 26 megacycles, for example, from oscillator 54, the frequency modulation of the latter wave by the wave of complex form being accomplished in the frequency modulator 53 to form a wave including a demodulating signal wave identical with the frequency modulation impressed upon the original carrier wave at modulator 5 of Fig. 1. The output of frequency modulator 53 is impressed upon the converter 52.

In order that the distorting frequency modulation introduced by frequency modulator 5 of the transmitter may be removed, the frequency shift of modulator 53 of the receiver 2 is made equal to the frequency shift of the corresponding modulator 5 of the transmitter. Then, since the complex wave form from device 42, in accordance with which the output of oscillator 54 is modulated, is also so selected as to be the same as that of the complex wave form from device 12, in accordance with which the output from oscillator 3 is modulated, therefore the total distortion introduced by the device 12 and frequency modulator 5 of transmitter 1 is removed in the converter 52.

The output of converter 52 comprises a new carrier wave, of 6 megacycles frequency in the present case, having the desired signal, in the form of frequency modulation from frequency modulator 7 of transmitter 1, superimposed thereon. From this new frequency-modulated carrier wave the desired signal is restored by means of the limiter 55 and the frequency modulation-to-amplitude modulation converter 56, and the signal is then impressed through the audio amplifier 57 upon the indicating device or loudspeaker 58.

Referring to Fig. 2, this figure illustrates a secret signaling system which is based upon and is an extension of the system illustrated in Fig. 1, and which may be found useful in special applications wherein an increased degree of secrecy over that obtainable by the system of Fig. 1 is desired. For this purpose in the system of Fig. 2 a distorting signal similar to that applied to the carrier wave, as described in connection with Fig. 1, is applied to the desired signal before the latter is impressed upon the carrier wave. The numerals 59 and 60 designate respectively the transmitter and the receiver of the more extended system based on Fig. 1 which is illustrated in Fig. 2.

The parts numbered 3 to 32 of the transmitter 59 are identical with the correspondingly numbered parts in the transmitter of Fig. 1 except that in order to supply a second wave of com-

plex form in addition to the complex wave supplied to frequency modulator 5, the amplifier and harmonic generator 12 in Fig. 2 is provided with a second set of control devices, 61 to 67, having a second set of switch means, as sockets 68 to 74, adapted to be connected in any desired combination by connection means including plugs, as 75 and 76, to a circuit to be presently described.

To provide a distorting modulation of the desired signal before it is applied at frequency modulator 7 to the carrier wave, the desired signal is impressed, from a signal source (not shown), through an amplifier 77 upon a mixer 78 upon which the output of a frequency modulator 79 is also impressed through an amplifier 80. An oscillator 81 producing a wave having a frequency preferably of 10,000 cycles per second is connected to the latter modulator 79, and a predetermined combination of the control means of harmonic generator 12 is also connected thereto, as in the present instance by plugs 75 and 76. In certain cases the oscillator 81 may be dispensed with and in place thereof the oscillator 11 or the harmonic generator 12 may be connected to the modulator 79. The mixer 78 is connected through the amplifier 14 to the frequency modulator 7.

It is necessary that a frequency shift which is relatively very high, of the order of 5,000 cycles plus or minus per second, be produced in the frequency modulator 79. The average frequency of this modulator being relatively low, of the order of 10,000 cycles per second or even less, the frequency shift therein must be 50 per cent or more. Because of the objectionable distortion encountered when the frequency shift extends over such a wide range, the desired shift is preferably obtained in any desired or known manner which will avoid this distortion, as by means (not shown) wherein a radio frequency wave, of 1000 kilocycles per second for example, is first modulated by waves having frequencies for example ranging up to plus or minus 5000 cycles per second, and then the resulting modulated wave is heterodyned down to the desired average frequency, as 10,000 cycles per second.

To prevent unwanted interception of the distorting signals from the transmitter 59 when the desired signals are not being radiated, the interlock 15 is interposed between amplifier 77 and 13, and an interlock 82 is interposed between amplifiers 77 and 80.

To provide a synchronizing signal for the transmitter 59 and the receiver 60, either the oscillator 11 or the harmonic generator 12 may be connected, through a switch as 83, to the amplitude modulator 9.

In the receiver 60 of Fig. 2 the parts numbered 33 to 37 and 52 to 58 are identical with the correspondingly numbered parts in the receiver 2 of Fig. 1. As in Fig. 1, an amplifier (not shown) may be added between converter 52 and limiter 55. Similarly to Fig. 1, the output of the intermediate frequency amplifier 37 of Fig. 2 is connected into two channels, 84 and 85.

In the channel 84 the output of amplifier 37 is impressed, through a rectifier 86 and a filter 87, upon an amplifier and harmonic generator 88 which is identical with the amplifier and harmonic generator 12 of transmitter 59.

In the other channel, 85, the output of amplifier 37 is impressed upon the converter 52 as in the receiver 2 of Fig. 1, and the converter 52, frequency modulator 53, oscillator 54, limiter 55,

and frequency-modulation-to-amplitude modulation converter 56 bear the same relation to each other as in the receiver 2. Further, similarly to receiver 2, the control means, for example 89, 90, and 91, representing a selected series combination of the fundamental and harmonics thereof in device 88 are connected to the frequency modulator 53, for example through the switch means 92 and 93, 94 and 95, and 96 and 97.

The frequency modulation-to-amplitude modulation converter 56 in receiver 60 of Fig. 2 instead of being connected through amplifier 57 to the signal responsive device or loudspeaker 58 as in receiver 2 of Fig. 1, is connected to a mixer 98. A frequency modulator 99 having a frequency shift equal to that of the corresponding modulator 79 of the transmitter 59 is also connected to the mixer 98. To this frequency modulator 99 are connected an oscillator 100, and also selected control means as 101 and 102 of the amplifier and harmonic generator 88 through switch means 103, 104 and 105, 106, corresponding respectively to control means 62 and 63 and switch means 75, 69 and 76, 70 of amplifier and harmonic generator 12 of transmitter 59. The switch means 103, 104 and 105, 106, are preferably connected to frequency modulator 99 through a phase shifter 107.

Under certain conditions the oscillator 100 may be dispensed with and the harmonic generator 88 may be connected to the frequency modulator 99 to supply the wave of the required frequency.

The mixer 98 is connected, through a low pass filter 108 and the amplifier 57, to the signal indicating means or loudspeaker 58.

In operation of the system of Fig. 2, a carrier wave from oscillator 3, frequency modulated in the modulator 5 in accordance with a distorting signal wave of complex form from the amplifier and harmonic generator 12 through the amplifier 13, is impressed upon the frequency modulator 7 through the amplifier 6. The operation up to this point is thus the same as described in connection with Fig. 1.

A desired signal in the 0 to 5,000 cycles per second frequency band for example, from the signal source (not shown) is impressed through amplifier 77 upon the mixer 78. The wave from oscillator 81 is frequency-modulated in modulator 79 in accordance with a distorting signal from amplifier and harmonic generator 12. The latter signal in the present case is constituted by the second and third harmonics, selected respectively by switch means 75, 69 and 76, 70. The resultant distorting frequency-modulated wave is also impressed, through amplifier 80, upon the mixer 78. The desired signal combined in mixer 78 with the distorting frequency-modulated wave from modulator 79 is impressed through the amplifier 14 upon the frequency modulator 7.

The distortion in the frequency modulated desired signal which leaves the frequency modulator 7 of Fig. 2 is thus not only due, as in the transmitter of Fig. 1, to the distorting signal impressed upon the modulator 7 from frequency modulator 5, but also to the distorting signal supplied through the mixer 78 from frequency modulator 79. In selecting the total distorting signal, the combination of harmonics and their amplitudes, from harmonic generator 2, which is impressed upon the frequency modulator 99 is, in general, different from the combination impressed upon the frequency modulator 5. The purpose is to render the derived audio signal unintelligible due to voice controlled masking frequencies. It is

obvious that the well-known forms of voice scrambling, speech inverting or other such systems may provide additional impediment to non-authorized reception.

5 Oscillations from oscillator 11 or from harmonic generator 12 are impressed through switch 83 upon the amplitude modulator 9 to produce a synchronizing signal. Undesired interception of the distorting signal when the desired signal is not being transmitted is prevented by interlocks 15 and 82 which operate in the manner previously explained in connection with Fig. 1.

The distorted signal from modulator 1 is impressed, as in Fig. 1, through amplifier 8, amplitude modulators 9 and power amplifier 10, upon antenna 4 and radiated therefrom.

In receiving the desired signal from the transmitter 59 by the receiver 60, the operation is substantially the same as that described in connection with the operation of receiver 2 of Fig. 1 up to the output side of frequency modulation-to-amplitude modulation converter 56. In the system of Fig. 2, however, the wave in the output of the converter 56 comprises, instead of the 6 megacycle carrier wave modulated only by the desired signal, a 6 megacycle carrier wave modulated by the desired signal which itself has previously been modulated in accordance with a distorting signal from frequency modulator 79 of transmitter 59.

The output of the frequency modulator 99, which includes a demodulating signal wave similar to the distorting frequency-modulated wave from frequency-modulator 79 of Fig. 1, enters the mixer and detector 98, to which the output of the converter 56 is also supplied. The output of mixer and detector 98 is impressed upon the low-pass filter 108 which is arranged, in the present case, to pass the 0 to 5,000 cycles per second frequency band. The desired signal, comprised in this band, is present in the output of mixer 98, being supplied to the mixer from converter 56. The output of filter 108 therefore represents only the desired signal, which is in this band. The restored desired signal after amplification in the amplifier 57 is supplied to the signal indicating device or loudspeaker 58.

It will be understood that in the secrecy signaling systems described herein additional degrees of secrecy may be obtained by applying known secrecy systems to the input signal. For example, inverted speech methods, speech scrambling, and methods involving the mixing and inversion of certain frequency bands, etc., as well-known in telephone practice, may be employed.

My invention has been described herein in particular embodiments for purposes of illustration. It is to be understood, however, that the invention is susceptible of various changes and modifications and that by the appended claims I intend to cover any such modifications as fall within the true spirit and scope of my invention.

What I claim as new and desire to secure by Letters Patent of the United States is:

65 1. In a secret signaling system, a transmitter comprising means to transmit a carrier wave and to modulate said carrier wave with a desired signal and a masking signal, said masking signal having harmonically related components, means to select said harmonically related components in accord with a prearranged code, a receiver for said carrier wave including means to generate in said receiver currents having any frequency comprised in said harmonically related components, 70 means in said receiver to select said frequencies

in accord with said code, means utilizing the frequencies selected in said receiver to suppress said masking signal as received in said receiver from said transmitter, means to transmit a synchronizing current of desired frequency between said transmitter and receiver, and means to synchronize the frequencies of said components of said masking signal and the frequencies corresponding thereto generated in said receiver by the frequency of said synchronizing current.

2. In combination, a transmitting station and a receiving station, means to transmit from said transmitting station a carrier wave modulated in accord with a desired signal, means in said receiving station to reproduce said signal from said carrier wave, and means to prevent undesired interception of said signal, said last means comprising means in each station to generate currents having a plurality of harmonically related frequencies and to select in each station one or any desired combination of said frequencies in accord with a prearranged code, means to transmit synchronizing current of desired frequency between said stations and to synchronize therewith all of said harmonically related currents in both stations, means in the transmitting station to modulate the frequency of said carrier wave in accord with currents having the selected frequency or frequencies, and means in said receiver utilizing the one or more of said harmonically related frequencies selected therein to remove said frequency modulation from said carrier wave.

3. The method of signaling secretly between a transmitting station and a receiving station which comprises modulating a carrier wave at the transmitting station with the signals to be transmitted and modulating the frequency of said carrier wave in accord with any one or more of a plurality of harmonically related frequencies, generating in said receiver currents having said harmonically related frequencies, synchronizing said harmonically related frequencies in both of said stations with a single frequency transmitted between said stations, and selecting said one or more of said frequencies in each station in accord with a prearranged code, receiving said frequency modulated carrier wave in said receiver and heterodyning it with oscillations having frequency varying in accord with said one or more of said harmonically related frequencies generated in said receiver thereby to produce a carrier wave free of modulation in accord with said one or more harmonically related currents, and reproducing the desired signal from said last mentioned carrier wave.

4. In a signaling system, a transmitter comprising means to frequency modulate a carrier wave in accordance with a distorting signal wave, means to frequency modulate said carrier wave in accordance with a desired signal wave, and means responsive to said carrier wave modulation in accordance with said desired signal to prevent said carrier wave modulation in accordance with said distorting signal wave in the absence of said carrier wave modulation in accordance with said desired signal.

5. In a signaling system, a transmitter, a receiver, means in said transmitter to frequency modulate in succession a carrier wave in accordance with a distorting signal wave and in accordance with a desired signal wave, means in said receiver to frequency modulate a second carrier wave in accordance with a distorting signal wave identical with said first-named distorting signal wave, means operatively associated with said

transmitter and said receiver to synchronize said last-named distorting signal wave with said first-named distorting signal wave, and means in said receiver including said second-named means to derive said desired signal wave from said first-named carrier wave.

6. In a signaling system, a transmitter comprising means to frequency modulate a carrier wave at a predetermined frequency shift in accordance with a distorting signal wave, means to frequency modulate said carrier wave in accordance with a desired signal wave, and means to amplitude modulate said carrier wave in accordance with a predetermined synchronizing signal wave, and a receiver comprising means to derive from said synchronizing signal wave a distorting signal wave identical with said first-named distorting signal wave, means to frequency modulate a second carrier wave at said predetermined frequency shift in accordance with said last-named distorting signal wave, and means including said last-named means to derive said desired signal wave from said first-named carrier wave.

7. In a signaling system, a transmitter comprising means to frequency modulate a carrier wave in succession in accordance with a distorting signal wave and in accordance with a desired signal wave, and means to amplitude modulate said carrier wave in accordance with a synchronizing signal wave for decoding of the resultant signal transmitted from said transmitter.

8. In a signaling system, a transmitter comprising means to frequency modulate a carrier wave at a predetermined frequency shift in accordance with a distorting signal wave, means to frequency modulate said carrier wave further in accordance with a desired signal wave, and means to amplitude modulate said carrier wave in accordance with a predetermined synchronizing signal wave for decoding of the resultant signal transmitted from said transmitter.

9. In a signaling system, a transmitter comprising means to frequency modulate a carrier wave in accordance with a distorting signal wave, means to frequency modulate said carrier wave in accordance with a desired signal wave, means to prevent said carrier wave modulation in accordance with said distorting signal wave in the absence of said modulation in accordance with a desired signal wave, and means to amplitude modulate said carrier wave in accordance with a synchronizing signal wave for decoding of the resultant signal transmitted from said transmitter.

10. In a signaling system, a receiver comprising means to receive a carrier wave frequency modulated in succession by a distorting signal wave and by a desired signal wave and amplitude modulated by a synchronizing signal wave, and means to derive from the synchronizing signal wave modulation of said received carrier wave a distorting signal wave identical with said first-named distorting signal wave.

11. In a signaling system, a receiver comprising means to receive a carrier wave frequency modulated in succession by a distorting signal wave and by a desired signal wave and amplitude modulated by a synchronizing signal wave, means to derive from the synchronizing signal modulation component of said received carrier wave a distorting signal wave identical with said first-named distorting signal wave, means to frequency modulate a second carrier wave in accordance with said last-named distorting signal wave, and means including said last-named

quency modulating means to derive said desired signal wave from said first-named carrier wave.

12. In a signaling system, a transmitter comprising means to frequency modulate a carrier wave in accordance with a distorting signal wave and means to frequency modulate the resulting carrier wave in accordance with a desired signal

wave, and a receiver adapted to receive said carrier wave, said receiver comprising means to generate a wave identical with said distorting signal wave and means including said last-named means to remove from said carrier wave said distorting frequency modulation thereof.

ELLSWORTH D. COOK.
